UNITED STATES PATENT OFFICE.

VINCENT OLIVER, OF PHILADELPHIA, PENNSYLVANIA.

DESIGN FOR A CASING FOR A VEHICLE SIGNAL LAMP.

Application filed June 10, 1925. Serial No. 13,723. Term of patent 3½ years.

To all whom it may concern:

Be it known that I, VINCENT OLIVER, a citizen of the United States, residing at Philadelphia, in the county of Philadelphia and State of Pennsylvania, have invented a new, original, and ornamental Design for Casing for a Vehicle Signal Lamp, of which the following is a specification, reference being had to the accompanying drawing, forming part thereof.

Figures 1, 2 and 3 are respectively a front, a side, and a rear elevation of a casing for a vehicle signal lamp, showing my design.

I claim:

The ornamental design for a casing for a vehicle signal lamp.

VINCENT OLIVER.
